Patented June 17, 1975

235,424

BOAT HULL

Leedice S. Smith, Elk, Wash. 99009

Filed Aug. 23, 1973, Ser. No. 390,890

Term of patent 14 years

Int. Cl. D12—06

U.S. Cl. D12—62

FIG 1

FIG 2

FIG 3

FIG 4

FIG. 1 is a side elevation view of a boat hull, the opposite side being a mirror of that shown;

FIG. 2 is a bottom view, a top view being in substantial conformance to the appearance shown in the bottom view;

FIG. 3 is an end view as seen from the left in FIG. 1; and

FIG. 4 is an end view as seen from the right in FIG. 1.

I claim:

The ornamental design for a boat hull, as shown and described.
